CLAIM

The ornamental design for a tool for crimping electrical terminal connections or the like, as shown and described.

DESCRIPTION

FIG. 1 is a left side elevation view of the tool for crimping electrical terminal connections or the like showing my new design;

FIG. 2 is a right side elevation view thereof;

FIG. 3 is a front elevation view thereof;

FIG. 4 is a rear elevation view thereof;

FIG. 5 is a top plan view thereof; and

FIG. 6 is a side perspective view thereof on an enlarged scale.

FIG. 5

FIG. 3

FIG. 2

FIG. 4

FIG. 1

FIG. 6
